UNITED STATES PATENT OFFICE.

FRITZ WITTSTOCK, OF BERLIN, GERMANY.

PROCESS FOR PRODUCING MOSAIC OR MARBLE PAPER.

No. 915,145.

Specification of Letters Patent. Patented March 16, 1909.

Application filed March 5, 1906. Serial No. 304,336.

To all whom it may concern:

Be it known that I, FRITZ WITTSTOCK, a subject of the Emperor of Germany, residing at Schönhauser Allee 84, Berlin, N., in the Empire of Germany, have invented a certain new and Improved Process for Producing Mosaic or Marble Paper, (Fancy Paper,) of which the following is a specification.

10 The production of variegated paper which is used especially by book-binders and card-board makers was hitherto effected in such a manner, that color was applied by means of a brush upon a gelatin-plate. Hereupon 15 the single sheets to be printed with colors were pressed upon the gelatin plate, dried and finally varnished. The product obtained in this manner, may have answered its purpose, but it is not possible, to produce 20 from a plate, which was prepared in an awkward and difficult manner, an unlimited number of colored paper sheets and moreover, there would be a difference in the pattern varying from one sheet to the other. 25 and any uniformity in a certain design would be out of question. When applying autotypy for this purpose, it will be impossible, to produce prints with entirely white spaces as even in the greatest intensity 30 of light, small black spots are to be found. Hitherto two methods are known to carry that process into practical effect. The oldest of them is, that a glass-plate, upon which is provided a glass-network or grain 35 plate with uniform horizontal or vertical lines, is taken in front of a very sensitive plate placed inside a photographic camera and exposed to the effect of light half of the time intended for exposure, whereupon the 40 camera will be closed and the grain plate brought into a different position. When the first half of the time for exposure has passed with horizontal position of the grain-plate, the second half will pass with vertical position of same. The result of this will be a 45 pattern, formed of lines crossing each other. A later method of this kind is to expose a glass plate upon which is laid a horizontal and vertical grain plate, to expose the sensitive plate only once for the time required to the light and the final result will be a pattern of lines crossing each other.

When applying autotypy and if for example marble colored paper is to be produced, by the old method, viz. by placing a simple grain plate in front of the sensitive

plate and exposing same without interruption, the necessary time to the effect of light, the final result will be, a simple structure of lines either in a horizontal or vertical direction, which depends on the position of the grain plate placed inside the camera, while, when exposing with double grain plates, entirely white spots will be shown with a remarkable distinctness, which is expressed 60 very strongly in papers having one and several colors. It is impossible to mark any difference in tint through a larger or smaller grain plate. By applying the chemical-physical process and making only one exposure with the simple grain plate, an object which contains white, light-gray and black shades will change in the reproduction as follows: White will remain completely white, 65 light gray will result from the use of a fine 70 grain plate, dark gray from the use of a larger grain plate and black according to the intensity of black spots in the original as such in the reproduction.

The asphalt process results in an inexact 80 reproduction of the marble grain, results in difficult printing and when enlarging the pattern, no union of the design will be possible. The chalk method is extremely difficult for making an imitation, gives any 85 amount of trouble in printing and an exact connection of the lines is out of question. By engraving the pattern, it is impossible to imitate any design in an exact manner.

In the practice of my process I may make 90 use of the above mentioned methods, but in my process I produce the result desired by the use of a single lithograph stone or plate, and at one printing operation.

In carrying out my process a grain plate 95 is placed in front of a sensitive plate of a photographic camera and a suitable object, as for example, a marble plate or a woven fabric, is used for a design. The plate having been exposed the necessary length of 100 time will show an exact likeness of the design photographed, the likeness, however, being divided by the lines of the grain plate as will be understood. The negative thus 105 produced is prepared by photographic means to be copied on paper as by the production of an autotype plate from the negative in the well known manner. Prints are then 110 made from the autotype plate, different colors being preferably used in making each print. The impressions on these prints are then transferred to a lithograph stone or equiva-

lent plate, the prints being shifted slightly so that the impressions are not coincident. Where different colored inks are used in making the prints or printed sheets the number of prints or printed sheets made in different colors from the autotype plate will of course, depend upon the number of colors required to produce the desired effect in the finished impression. The slight shifting of each print or printed sheets with respect to each other, in transferring their impressions one above the other to the stone or plate results in the production of unexcelled marble paper effects.

It is to be understood that, while I prefer to use different colored inks in making the prints or printed sheets, the invention may be practiced by printing with the same colored ink upon the prints or printed sheets, the slight shifting of the sheets, which constitutes the essential features of my invention, being done as hereinbefore described. Where the stone or plate has applied thereto only ink of one color, it is reinked in the usual way. When however, inks of different colors are applied thereto, as hereinbefore described, the reinking is accomplished in the same manner as that in which the first ink is applied. This has been hereinbefore set forth.

It is to be understood that the original negative may be reproduced in different colors upon the separate prints or sheets by any known methods and that in the production of the stone or plate to be used in the final printing, scraping knives or other

means may be employed to effect corrections in the stone or plate where the color is too heavy or the lines too close together and that weak spots or parts showing lines too far apart may be filled in with color by means of a gelatin plate or screen, in accordance with the present practice in the art.

Having thus described my invention, I claim:

1. The herein described process which consists in photographing a design through a grain plate, reproducing said design upon separate prints or sheets, transferring the different impressions of the said prints or sheets to a stone or plate, one impression being superimposed upon another, but each impression being shifted somewhat from exact coincidence with adjacent impressions, and finally printing from said stone or plate.

2. The herein described process which consists in photographing a design through a grain plate, producing an autotype from the negative thus made, producing separate impressions in different colors from said autotype, superimposing said impressions one above the other, but somewhat out of exact coincidence, upon a lithograph stone or analogous plate and finally printing from said stone or plate.

In testimony whereof I affix signature in presence of two witnesses.

FRITZ WITTSTOCK.

Witnesses:

HENRY HASPER,
CHARLOTTE BUSSLINGER.
